Primary Examiner — Caron Veynar*Assistant Examiner* — Abraham Bahta(74) *Attorney, Agent, or Firm* — Fitch, Even, Tabin & Flannery(57) **CLAIM**

The ornamental design for a sleeve for containers, as shown and described.

DESCRIPTION

FIG. 1 is a perspective view of a sleeve for containers showing our new design;

FIG. 2 is a top plan view thereof;

FIG. 3 is a right side elevational view thereof, the left side elevational view being the mirror image thereof;

FIG. 4 is a bottom plan view thereof; and,

FIG. 5 is a front elevational view thereof; the rear elevational view being the mirror image thereof.
